GREASE GUN HEAD

Edwin P. Sundholm, Albert City, Iowa

Filed Apr. 19, 1962, Ser. No. 69,770

Term of patent 14 years

(Cl. D46—1)

FIG. 1 is a perspective view of a grease gun head embodying my new design;

FIG. 2 is a side elevational view of the grease gun head of FIG. 1, the portion shown in broken lines being included for purpose of illustration only;

FIG. 3 is a top plan view of the grease gun head;

FIG. 4 is a side elevational view of the grease gun head as seen from the left with respect to the preceding figures; and

FIG. 5 is a side elevational view of the grease gun head as seen from the right hand side.

I claim:

The ornamental design for a grease gun head, as shown and described.
